(57) **CLAIM**

The ornamental design for a pet carrier, as shown and described.

DESCRIPTION

FIG. 1 is a front view of the pet carrier showing our new design.

FIG. 2 is a back view thereof.

FIG. 3 is a left side view thereof.

FIG. 4 is a right side view thereof.

FIG. 5 is a top view thereof.

FIG. 6 is bottom view thereof.

FIG. 7 is a front perspective view thereof.

FIG. 8 is another back view thereof in an alternate position; and,

FIG. 9 is an enlarged back perspective view showing the inside of the pet carrier.

The broken lines in the drawings are for illustration only and form no part of the claimed design.
